UNITED STATES PATENT OFFICE

166,583

POULTRY HANGING SHACKLE

Ralph S. Zebarth, Hickman Mills, Mo., assignor
to Gordon Johnson Company, Kansas City, Mo.,
a corporation of Missouri

Application May 21, 1951, Serial No. 15,277

Term of patent 14 years

(Cl. D11—1)

To all whom it may concern:

Be it known that I, Ralph S. Zebarth, a citizen of the United States, residing at Hickman Mills, in the county of Jackson and State of Missouri, have invented a new, original, and ornamental Design for a Poultry Hanging Shackle, of which the following is a specification, reference being had to the accompanying drawing, forming a part thereof.

Fig. 1 is a front elevational view of a poultry hanging shackle, showing my new design.

Fig. 2 is a side elevational view thereof.

Fig. 3 is a top plan view thereof; and

Fig. 4 is a sectional view on line IV—IV of Fig. 1 of the poultry hanging shackle.

I claim:

The ornamental design for a poultry hanging shackle, as shown.

RALPH S. ZEBARTH.
